**BOWLING ALLEY WITH SKILL
 EQUALIZING MEANS**
 Joseph R. Winkleman, 3980 Highland Drive,
 Mogadore, Ohio 44260
 Filed Oct. 23, 1965, Ser. No. 503,863
 6 Claims. (Cl. 273—51)

This invention relates to a tenpin bowling game for amusement.

In the standard game of tenpin bowling, utilizing a smooth wooden runway, and a large hard rubber or synthetic resin ball to knock down the pins, a substantial segment of the bowling fraternity qualifying for league play may, because of consistently high scoring ability, find it difficult to be accepted in fun games enjoyed by bowlers of lower average scoring ability. Accordingly, these high scorers may miss some of the enjoyment of bowling with groups of friends who have relatively low average scoring ability.

An object of this invention is to provide a device adapted for combination with a standard bowling lane for equalizing the scoring of bowlers within a wide range of scoring ability.

Another object of the invention is to provide a device of the character described for easy attachment to a standard bowling lane floor without damaging the same.

Other objects of the invention will be manifest from the following brief description and the accompanying drawings.

Of the accompanying drawings:

FIGURE 1 is a perspective view of a tenpin bowling alley embodying the features of the invention;

FIGURE 2 is an enlarged cross-section taken on the line 2—2 of FIGURE 1;

FIGURE 3 is a top plan view of one of the baffles, on a reduced scale.

Referring to FIGURE 1 of the drawings, the numeral 10 designates a tenpin bowling alley, including a smooth surfaced floor 11 of longitudinally extending jointed wood boards, defined between opposite gutters 12, 12; tenpins 13, 13 spotted in a triangular pattern at the forward end; a foul line 14 at the other end; and laterally spaced guide marks 15, 15 forwardly of the foul line. With this arrangement, expert bowlers can normally roll balls with respect to the guide marks 15, along a path P, to knock down a maximum number of pins 13 and average a score between 190 and 250 pins, or more. The paths of the balls rolled by the expert bowlers follow a somewhat definite curved path along one side of the alley to head pins one and three, as indicated in chain-dotted lines in FIGURE 1, to result in "strikes" by which all of the pins are knocked down. The present invention contemplates provision of means on the alley surface which will require the expert to change his style of bowling and thereby reduce his scoring ability in a fun game.

To this end, a series of baffles 16, 16 in the form of long, narrow, strips are cemented or otherwise adhered to the floor 11, along the right side of the alley, in laterally staggered, longitudinally spaced relation, so that at least one strip most likely will be directly in the curved path of the ball, substantially as shown in FIGURE 1. The pattern of the strips may be substantially duplicated along the left side of the alley for left-handed bowlers. As an example, each strip 16 may be four feet long by two inches wide, by one-sixteenth inch thick, and having plano-convex cross-sectional shape, the convex upper side of which terminates in feathered edges along opposite side edges of the strip and at rounded ends 17, 17 of the strip, as best shown in FIGURES 2 and 3. The strips may be of flexible elastic material, such as rubber, ad-

2

hered to the floor 11 by means of a tacky adhesive which permits easy removal thereof from the floor without damaging the surface of the same. This facilitates rapid relocation of the strips to suit the particular conditions, such as with reference to relative differences in bowling skill of the players.

In use of the improved game apparatus shown in FIGURE 1, the usual rules of bowling are followed with respect to scoring. The scores of the more skillful bowlers, however, will be reduced because any tendency on their part to roll the balls along a preferred curvate path will result in lowering of the expected scoring. Less skillful bowlers, on the other hand, following straighter paths C and D to avoid over-riding the baffle strips 16, will in general tend to score somewhat on a par with the normally high scorers. Accordingly, in use of the improved game equipment bowlers having mixed scoring skills tend to have comparative scores which are generally equalized. In other words, the present invention makes it possible for bowlers of varying skills to get together in fun games for mutual enjoyment, without adversely affecting their normal playing abilities.

Modifications of the invention may be resorted to without departing from the spirit thereof or the scope of the appended claims.

What is claimed is:

1. The combination with a tenpin bowling lane having a smooth playing surface, spots at one end for a tenpin set-up in triangular arrangement, and visible guides for pre-estimating various paths of rolling movement of a ball for requisite scoring results; at least one series of generally thin, flat baffles attached to said playing surface; the baffles of said series being predeterminedly variously spaced from the longitudinal center-line of the lane so that at least one element will be at least partly in the path of rolling movement of a ball delivered by a player of a given class of above average bowlers; edge portions of the elements being of reduced thickness to minimize effectiveness of the elements for predetermining the course of a ball rolled into engagement therewith.

2. The combination as set forth in claim 1, said baffles being of plano-convex cross-section, with the convex side uppermost and converging to feathered edges.

3. The combination as in claim 2, the planar underside of said baffles being releasably attached to the playing surface by a coating of tacky, plastic adhesive.

4. The combination as in claim 3, said baffles being of rubber-like elastic material.

5. The combination as in claim 4, including one said series of baffles at opposite sides of the longitudinal center-line of the lane.

6. The combination as in claim 1, including one said series of baffles at opposite sides of the longitudinal center-line of the lane.
